UNITED STATES PATENT OFFICE.

GUSTAVE C. MARX, OF ELIZABETH, NEW JERSEY, ASSIGNOR TO DIEHL MANUFACTURING CO., OF ELIZABETH, NEW JERSEY, A CORPORATION OF NEW JERSEY.

SEWING-MACHINE MOTOR.

1,369,452.

Specification of Letters Patent. Patented Feb. 22, 1921.

Application filed September 30, 1915. Serial No. 53,345.

To all whom it may concern:

Be it known that I, GUSTAVE C. MARX, a citizen of the United States, residing at Elizabeth, in the county of Union and State 5 of New Jersey, have invented certain new and useful Improvements in Sewing-Machine Motors, of which the following is a specification, reference being had therein to the accompanying drawings.

10 This invention relates to sewing machine motors.

One object of the invention is to provide an improved support for a sewing machine motor.

15 Another object is to provide improved means for pivotally supporting the motor upon that portion of the sewing machine frame which is above the bed plate.

Another object is to provide a support for 20 the motor which may be fixed to a part of the sewing machine frame and which will permit the motor to be moved in at least two planes from its operative position to an inoperative position where it will be entirely 25 out of the way.

Other objects will appear as the specification proceeds.

The invention is illustrated in the accompanying drawings, in which—

30 Figure 1 is a rear elevation of the upper portion of a sewing machine to the frame of which is attached the improved motor support and motor.

Fig. 2 is a plan of the structure shown in 35 Fig. 1.

Fig. 3 is an end elevation of the structure shown in Fig. 1 with the balance wheel removed.

Fig. 4 is an enlarged transverse sectional 40 view of a portion of the sewing machine frame with the motor support applied thereto.

Fig. 5 is a plan of the motor support with the parts in inoperative or motor-retracted 45 position.

Fig. 6 is a partial sectional view of Fig. 5, and

Fig. 7 is a detail sectional view of one of the interlocking connections between the 50 sections of the support.

In its preferred form the support is constructed in the form of a two part bracket of which one section is constructed as a base member with a cover plate rigidly secured 55 to the frame as a closure for the access open-

ing in the hollow arm. The other section of the bracket, to which the motor is rigidly secured, is mounted upon the base member by a connecting element having angularly disposed pivotal pins journaled in the respective bracket sections to form a connection between the two that will permit movement of the motor from operative position to an inoperative position under the arm of the sewing machine head. The motor supporting section is formed with tongues adapted to enter grooves or slots in the base section in which they are adapted to be maintained by gravity to confine the motor in either its operative or inoperative position.

In the operative position of the motor it is so sustained that a grooved friction wheel upon its shaft rests upon the balance or driving wheel of the sewing machine. In the inoperative position of the motor it is 75 maintained beneath the lateral member or arm of the sewing machine head where it is entirely out of the way and will not interfere with placing a cover over the sewing machine head or dropping the head if the 80 sewing machine be of the drop-head type.

That part of the sewing machine structure above the bed plate 1, commonly known as the head, comprises in general a hollow standard 2 with the lateral tubular arm 3 85 in which is journaled the shaft 4 carrying at its rearward end the driving or balance-wheel 5. The standard 2 has in its rear side at its junction with the arm 3 the usual aperture 6 (Fig. 4) for access to the parts 90 within the arm.

The motor is preferably of electrically-driven type and comprises the frame 7 of usual or suitable form in which is journaled the armature-shaft 8 carrying the grooved 95 friction-wheel 9 which preferably has an operative face formed by a cork band or ring adapted to rest upon and roll in contact with the driving wheel 5. The motor receives its electric current through the cable 10 leading into an aperture in the frame 7, as usual.

The motor-frame 7 is secured by means of fastening screws 11 upon a concaved seat afforded by the upper or outer face of the 105 plate 12 at one end of the arm 13 whose other end is formed with a fork 14 which embraces a swivel-block 15 to which it is pivoted by means of the transverse pin 16. The block 15 constitutes the head of a sec- 110

ond pivotal pin 17 arranged at right angles to the pin 16 and journaled in an aperture in a boss 18 at the outer end of a rigid arm 19 formed upon the cover-plate 20 which 5 affords a closure for the opening 6 in the sewing machine frame standard 2. To the outer end of the pin 17 are applied the washer 21 and nut 22 by means of which the pin is held in position in its aperture. The 10 plate 12 and arm 13 constitute the motor-supporting section of the motor-bracket of which the other section comprises the arm 19 and cover-plate 20.

As represented particularly in Fig. 4, the 15 cover-plate 20 is attached to the frame at the top by means of a screw 23 and at the bottom by a screw 24 tapped into the angle-piece 25 between which and the adjacent marginal portion of the plate 20 the marginal wall of the opening 6 is thus securely clamped.

The plate 12 is provided at one end with the depending tongue 26 which is adapted to enter a slot 27 in the lateral lug 28 upon 25 the cover-plate 20 when the motor is in operative position, as represented in full lines in Figs. 1 to 4, with its friction-wheel 9 in rolling contact with the driving wheel rim 5. As will be observed, the horizontal ful- 30 crum-pin 16 of the motor-supporting arm 13 permits the motor to descend freely by gravity for engagement of the friction-wheel 9 with the driving wheel 5, and the pressure of these parts is regulated by means 35 of the stop-screw 29 which is tapped into the ear 30 projecting from the lug 28 with its point serving as a rest for the lower face of the motor-supporting plate 12, as represented in Figs. 1 and 4. The stop-screw 29 40 is provided with the usual jam-nut 31 to hold it against turning.

When the machine is not in use, the motor 45 may be shifted from its full-line position above the arm 3 and at the rear of the stand- 50 ard 2 to its retracted position beneath the arm 3, as represented in dotted lines in Figs. 1 and 2. In performing this shift, the motor is turned to the right about the fulcrum-pin 16 to bring it close to the bed-plate 1, after which it is swung beneath the arm 3 upon the vertical fulcrum-pin 17, a 55 tongue or rib 32 upon the arm 13 entering the groove 33 of the arm 19, as represented particularly in Figs. 6 and 7 to provide a positive lock for holding the motor in retracted position.

It is evidently immaterial to the present improvement what types of sewing machine and motor be employed, and it is equally 60 evident that the form and arrangement of component parts of the motor-bracket may be materially modified within the scope of the invention. While in the present embodiment of the improvement use is made of a 65 joint comprising pivotal pins disposed in

angular relation, other suitable forms of joint may be employed if desired.

Having thus set forth the nature of the invention, what I claim herein is:—

1. The combination with a sewing machine frame of a bracket, a supporting arm pivoted thereto, a motor carried by said arm, said arm being capable of swinging movement in at least two planes to move the motor bodily to or from its operative position, and locking means for confining said arm in two positions corresponding to the operative and inoperative positions of the motor. 70

2. The combination with a sewing machine frame of a bracket, a supporting arm pivoted thereto and a motor carried by said arm, said arm being capable of a swinging movement about a horizontal axis and about a vertical axis to move the motor to and 85 from its operative position.

3. The combination with a sewing machine, of a motor, a bracket for supporting the motor in either its operative or inoperative position, said bracket comprising a 90 motor supporting section and a base section, and a connecting element provided with angularly disposed pivotal pins journaled respectively in said sections of which one is journaled in the supporting section and the 95 other in the base section to permit movement of the motor supporting section in at least two planes to move the motor to and from its operative position, and interlocking means provided upon said sections for 100 maintaining them in different predetermined relative positions.

4. In combination with a motor-frame, a motor-bracket comprising a motor-frame supporting section, a base section, a connecting element provided with angularly disposed pivotal pins journaled respectively in said sections, and a plurality of tongue-and-slot connections between said sections independent of their pivotal connection and 110 adapted to be maintained in interlocking relation by gravity.

5. The combination with a sewing machine frame constructed with a hollow member formed with an opening for access 115 to its interior and having journaled therein a shaft carrying a driving wheel, of a motor-bracket comprising a base member formed with a cover-plate for said opening of the sewing machine frame having means 120 for rigidly securing it to the latter, a motor-supporting member sustaining a motor comprising a shaft having a friction-wheel adapted for engagement with said driving wheel, said supporting member having a 125 pivotal connection with the base member whereby in one position of the supporting member the motor friction-wheel is sustained by gravity in operative relation with the driving wheel, and means for confining 130

said supporting member movably in operative position.

6. The combination with a sewing machine having the usual frame structure above the bed plate of a bracket adapted to be attached to said frame structure, and means for movably supporting a motor from said bracket so that the same may be moved in at least two planes from driving position to a position under the arm of said frame structure.

7. A bracket adapted to be attached to a sewing machine frame having an arm, said bracket having a motor supporting arm movable in at least two planes so that the motor may be moved from a driving position to a position beneath the arm of the sewing machine frame.

8. The combination with a sewing machine, of a motor, a bracket for supporting the motor in either its operative or inoperative position, said bracket comprising a

base section and a motor supporting section pivotally connected thereto and permitting movement of the motor to and from its operative position, and interlocking means provided on said section for maintaining them in different predetermined relative positions.

9. A bracket adapted to be attached to a sewing machine frame and to support a motor in either its operative or inoperative position, said bracket comprising a base section adapted to be attached to the sewing machine frame, a motor supporting section pivotally connected to the base section and adapted to permit movement of the motor to and from its operative position, and interlocking means provided upon said sections for maintaining them in different predetermined relative positions.

In testimony whereof, I have signed my name to this specification.

GUSTAVE C. MARX.
